US00D669373S

(12) **United States Design Patent**
Genet-Jegard et al.

(10) **Patent No.:** **US D669,373 S**
(45) **Date of Patent:** **** Oct. 23, 2012**

(54) **RING OF DOSIMETRY**

(75) Inventors: **Sophie Genet-Jegard**, Villebon sur Yvette (FR); **Alexandre Hoeffel**, Orsay (FR); **Patrice Fraboulet**, Paris (FR)

(73) Assignee: **Institut de Radioprotection et de Nucleaire**, Fontenay aux Roses (FR)

(**) Term: **14 Years**

(21) Appl. No.: **29/381,836**

(22) Filed: **Dec. 23, 2010**

(30) **Foreign Application Priority Data**

Jun. 23, 2010 (FR) 10 3373

(51) **LOC (9) Cl.** **10-04**

(52) **U.S. Cl.** **D10/47**

(58) **Field of Classification Search** ..... D10/47; 24/627; 40/639; 63/1.13, 15, 29.1, 40, DIG. 3; 250/483.1, 484.2, 484.3

See application file for complete search history.
